UNITED STATES PATENT OFFICE.

LOUIS M. CANDIDUS, OF BROOKLYN, E. D., NEW YORK.

APPARATUS FOR CURING TOBACCO.

SPECIFICATION forming part of Letters Patent No. 224,142, dated February 3, 1880.

Application filed October 29, 1879.

To all whom it may concern:

Be it known that I, LOUIS M. CANDIDUS, of Brooklyn, E. D., in the county of Kings and State of New York, have invented a new and 5 useful Improvement in Apparatus for Curing Tobacco, of which the following is a specification.

The object of my invention is to cure leaf-tobacco by means of steam without contact 10 between the steam and tobacco, and at the same time carry off the vapors expelled from the tobacco.

In the accompanying drawings, Figure 1 is 15 a vertical cross-section of my improved apparatus for curing tobacco, taken on line $x-x$ of Fig. 2. Fig. 2 is a vertical longitudinal section taken on line $y-y$ of Fig. 1; and Fig. 3 is a horizontal section of the apparatus, taken on line $z-z$ of Fig. 2.

20 Similar letters of reference indicate corresponding parts.

Referring to the drawings, my improved apparatus consists of a steam chest or case, A, provided at one end, B, with a rabbeted door, 25 C, having the rabbeted joint a packed with rubber b . Door C is held in place by bars D, which have their ends placed in loops or staples c .

The door C is forced into place by wedges 30 d , driven under the staples c against said bars, so that a steam-tight joint can be formed between the said door and the case A. At the same time the door C can be quickly and easily removed by taking out wedges d and 35 removing the bars D.

Inside of case A is provided a metal tank, E, with an overflow-pipe, e , extending through the side of the case. On the floor of the tank are laid strips f , and on these strips are placed, 40 at right angles to the door C, skids F F.

g is a steam-inlet pipe leading through the wall of case A.

G is the close receptacle for the tobacco. It is composed of a rectangular box, h , of a 45 length that will permit it to be passed through the doorway of case A.

Inside of receptacle G, and at each end, are provided perforated partitions i i , dividing off spaces j j . The receptacle is provided with a 50 close-fitting cover, H, held on by bolts k , passed through the said cover, and nuts l , screwed down on said cover. The cover is intended to be fitted to the receptacle so as to form a steam-tight joint therewith.

Cover H is provided with short pipes m , 55 which open into a drum, I. Said drum is provided with a pipe, K, in position to be coupled in any suitable manner with a pipe, L, passed down through the roof of case A.

The manner of using the apparatus is as 60 follows: The "hands" of tobacco are laid in the receptacle G, with their butts against the perforated partitions i i , until the said receptacle is nearly filled. The top H is then placed over the receptacle and fastened to box h by 65 any suitable devices, so as to form a steam and water tight joint with said box, which is then placed in case A on skids F and the pipe L joined to pipe K. Door C is then put in place and barred. Steam is then admitted 70 to the interior of case A through pipe g .

The heat from the steam, by sweating the tobacco, drives out the properties of the tobacco which give it the offensive odor and bitter taste. These properties pass off in the 75 form of a vapor. Said vapor is prevented by the overlying hands from rising up through the tobacco; but it is permitted to pass endwise between the layers. The vapor being thrown off in this way, it passes through the 80 perforations in partitions i into spaces j , and, rising up above the mass of tobacco in receptacle G, it passes again through the perforations into the upper part of receptacle G, and thence it escapes through pipes m , drum I, 85 and pipes K L. The course the vapors take is indicated by the arrows in Fig. 1.

Care must be taken not to pile the hands too high in the receptacle G, as it is necessary to the proper working of the invention that 90 the upper perforations in partitions i shall remain open, so that the vapors can pass freely from the spaces j back into the upper part of receptacle G.

Having thus described my invention, I claim 95 as new and desire to secure by Letters Patent—

The receptacle G, provided with perforated partitions i i , in combination with steam and water tight cover H, pipes m , drum I, pipes K 100 L, and a suitable chest or case for the reception of said receptacle, substantially as described.

LOUIS M. CANDIDUS.
